UNITED STATES PATENT OFFICE.

GREENLEAF WHITTIER PICKARD, OF NEWTON CENTER, AND JOHN ALBERT PROCTOR, OF LEXINGTON, MASSACHUSETTS, ASSIGNORS TO WIRELESS SPECIALTY APPARATUS COMPANY, OF BOSTON, MASSACHUSETTS, A CORPORATION OF NEW YORK.

VERNIER FOR TUNING REACTANCES.

Application filed November 8, 1924. Serial No. 748,552.

To all whom it may concern:

Be it known that we, GREENLEAF WHITTIER PICKARD and JOHN ALBERT PROCTOR, citizens of the United States of America, residing, respectively, at 59 Dalton Road, Newton Center, and 21 Parker Street, Lexington, State of Massachusetts, have invented a certain new and useful Vernier for Tuning Reactances, of which the following 10 description, in connection with the accompanying drawings, is a specification.

This invention relates to verniers for electrical tuning devices, particularly those employed in radio communication, and more particularly for variable air radio tuning condensers.

The objects of the invention include that of providing a vernier whose capacity variation per degree of movement is approximately proportional to the main condenser capacity.

The invention consists of the constructions and arrangements described herein and illustrated, by way of example, in the drawing, which is a perspective and somewhat diagrammatic view of an embodiment of the invention. Prior verniers have had the defect that at the low capacity end of the main condenser scale, the vernier adjustment is not fine enough relative to the main condenser; while at the high capacity end of the main scale, the vernier adjustment is too fine, i. e., the entire scale of the vernier is not enough.

In the drawing, the main condenser is shown at the right, as comprising a rotatable spindle S carrying at its right-hand end an operating handle MH and a pointer CI operating over a suitable scale not shown. Spindle S carries the movable condenser plates MP, which are rotated by the spindle. Between said movable plates are located the fixed plates FP of the condenser; the successive plates being separated from one another by air as the dielectric.

At the left is shown the vernier shaft VS, carrying at its right end a vernier handle VH and a pointer VI operating over a suitable scale, which may or may not be the same scale over which operates pointer CI of the main condenser.

On the left end of spindle S is mounted a condenser plate CP. On the left end of ver-

nier spindle VS is mounted a condenser plate VP. Condenser plates CP and VP are separated from one another by an air space constituting a condenser dielectric.

The capacity of the entire device, including that of the main condenser MP—FP, and the capacity between auxiliary plates CP and VP, is included in the circuit indicated on the drawing of which the terminals are T¹ and T², lead X extending from spindle S to terminal T¹ and lead Y extending from spindle VS to terminal T².

The invention involves the relation between condenser plates CP and VP.

Plate CP is shown as having a certain curvature, so that when in the position shown (the full capacity of the main condenser being in the circuit, due to the intermeshing of all the plates MP and FP), plate CP offers the greatest opposing surface to the vernier plate VP. Thus in the positions of plates CP and VP shown, the capacity change in the vernier for a given movement of vernier handle MH is a maximum, i. e., the largest change for a given movement of handle VH. Conversely, when the capacity of the main condenser is at a minimum (as when plates MP are turned entirely out of mesh with fixed plates FP), then plate CP also will have been so rotated as to present minimum opposing surface to vernier plate VP. Thus any adjusting movement of VP by handle VH will produce a minimum variation of capacity in the circuit T¹, T².

Thus the invention provides a vernier having a capacity variation per degree of movement which is approximately proportional to the capacity of the main variable condenser at any condition of the latter.

Preferably, the relation of the curvatures of plates CP and VP is such that the variation in capacity produced by operation of vernier handle VH is the same percentage of the capacity of the main condenser at any setting of main condenser handle MH.

The invention may take various forms. In the embodiment shown, plate CP is more or less disk-shaped and is mounted eccentrically on main spindle S; and vernier plate VP is formed with a semicircular movable end adjacent to plate CP. That is, plate CP and VP are shaped, at their over-lapping

portions, so as to produce a change of capacity, by movement of vernier handle VH, which is substantially proportional to the capacity of the main condenser at any of the 5 various settings of the latter as an adjustable device.

If desired, vernier handle VH and its shaft VS may be concentric with handle MH and shaft S of the main condenser. In that case, 10 of course, plate CP would be insulated from its shaft S, and vernier plate VP mounted on its shaft VS located concentric with shaft S. Plate CP in such case should be insulated from shaft S, although mounted thereon and 15 rotated thereby, because the concentric structure of shafts S and VS preferably would result in electrically connecting the two concentric shafts. In this case, plate CP may be eccentrically mounted on shaft 20 S, but plate VP, mounted on shaft VS, is concentric with shaft S, thus requiring a change of shape or curvature of either VP or CP or both, as compared with the shapes illustrated in the drawing.

25 The invention is not limited to a variable condenser with an air dielectric, as shown, for the dielectric may be of solid material such as mica between movable metallic plates. Nor is the invention limited to 30 application to variable condensers, for it may be applied to variable inductance tuners.

It is to be understood that the invention 35 is not limited to the embodiments and features specifically shown and described herein, but that such embodiments and features are subject to changes and modifications without any departure from the spirit of the invention.

We particularly point out and distinctly 40 claim the part improvement or combination

which we claim as our invention or discovery, as follows:—

1. A vernier for a rotatable condenser, which comprises an auxiliary condenser plate mounted eccentrically on the shaft of 45 the condenser; a rotatable vernier shaft parallel with the main condenser shaft; and a vernier condenser plate mounted rotatably on the vernier shaft; the condenser plate on the main condenser shaft having a disklike 50 shape, and the condenser plate on the vernier shaft having an approximately semicircular end adjacent the auxiliary plate on the main condenser shaft.

2. A vernier for a variable tuning condenser, which comprises an auxiliary condenser plate rotatably mounted on the shaft of the main condenser and a vernier condenser plate co-operating therewith, said co-operating plate having curvatures of their 60 overlapping portions which cause a change of capacity by operation of the vernier plate which is substantially proportional to the capacity of the main condenser at any setting 65 of the latter.

3. A vernier for a variable tuning reactance, which comprises an auxiliary reactance element controlled by the main reactance, and a vernier reactance element co-operating with said auxiliary element; said 70 co-operating reactances having interrelated portions which, upon movement of the vernier reactance, cause a change which is substantially proportional to the value of the main reactance at any setting of the 75 latter.

In testimony whereof we have signed our names to this specification.

GREENLEAF WHITTIER PICKARD.

JOHN ALBERT PROCTOR.
